UNITED STATES PATENT OFFICE.

HARRY E. BRICKER, OF INGOMAR, PENNSYLVANIA, ASSIGNOR TO NATIONAL METAL PRODUCTS COMPANY, OF PITTSBURGH, PENNSYLVANIA.

WEATHER STRIP.

Application filed April 4, 1928. Serial No. 267,277.

This invention relates to the art of metal weather strips and refers to an improved construction particularly adapted to casement or swinging windows. It has in view 5 to provide a compound strip construction having a tongue and groove engagement when closed, by means of a sheet metal trough-shaped sill member and a co-acting sheet metal sash member adapted to open 10 and close therewith for sealing and protecting engagement.

In the drawings showing one preferred embodiment of the invention:

Fig. 1 is a vertical sectional view showing 15 the sash in operative position and with the two members of the compound strip in engagement;

Fig. 2 is a similar view, showing the sash partly closed towards the strip;

20 Fig. 3 is a perspective detail view of the sash member;

Fig. 4 is a similar view of the sill member;

25 Fig. 5 is a partial face view of the sill member.

Referring to the drawings, the window sash A is of the usual casement or swinging type, hinged at one side and adapted to swing towards and from and over the usual 30 sill B.

The main sealing elements against weather, wind, rain, etc., are the box-shaped strip C mounted on the sill and adapted to make tongue and groove engagement with the coping member D, and also with the sash.

35 Strip C is formed of suitable thin sheet metal, preferably non-corrosive, as zinc, bronze, etc., shaped by dies from a blank to form it into the cross sectional shape shown, 40 of any suitable length.

The middle portion 2 is adapted to be attached to the sill by screws 3, through holes 4 therein as shown. The front or outer portion 5 of the strip is formed by bending 45 the blank upwardly and outwardly at an angle of 45° more or less to the plane of the bottom contacting surface, and then inwardly, parallel to the bottom plane, providing the sealing tongue or flange 6.

50 The back or inner portion of the sill strip is formed by bending the other side of the blank upwardly at right angles to the plane of the base providing the inner wall or flange 7.

55 The sash A as shown is rebated as at 8

whereby to provide clearance and an abutting shoulder for engaging the flange 7 when closed, as in Fig. 1. Such engagement limits the movement of the sash while also forming a contacting seal. 60

For the purpose of effecting a close sealing engagement with the tongue 6, the sash member D having the lower tongue engaging flange or groove, the outwardly protecting coping, and the upper attaching flange is 65 provided. Member D is similarly made of sheet metal bent from a blank to form an attaching flange 9 having screw or nailing openings 10 for securing attachment to the outer face of the sash A sufficiently above 70 the level of the tongue 6 for engagement therewith.

The upper edge of flange 9 is bent inwardly slightly, as shown, for good contact against the face of the sash when secured 75 thereto by the screws or nails.

Extending outwardly and downwardly from the flange 9 is the coping wall 11 bent around inwardly as at 12, forming the rounded edge and the inwardly extending 80 bottom wall 13.

Said wall is rounded reversely on itself, as at 14, and extends outwardly with the intervening groove 15 terminating in the flange 16, preferably turned down slightly, 85 as shown.

As thus formed, the coping D provides a fender coping or protector adapted to shed water outwardly and away from the sill member when engaged therewith, and to 90 closely contact with and engage the tongue 6 by the double-sided groove 15, or merely by the lower flange 16.

The coping D as thus made and secured by its upper edge is sufficiently resilient to 95 adapt itself to the tongue in closing and opening, while the rounded edge 14 bears back against the face of the sash, ensuring resistance in closing against the tongue 6.

When thus closed the parts are in comparatively tight engagement, completely sealing the joint. 100

The sill member C provides a trough or gutter between its front sloping wall 5 and rear flange 7 for collection of water or snow 105 that may pass inwardly over its front flange 6, as when the window is wholly or partly open.

At suitable intervals along the lower front portion of wall 5 are provided leak or weep 110

holes 17 formed by partly severing the metal and forcing it downwardly and outwardly, as at 18. By such arrangement the tongue 18 effectively prevents the action of wind currents tending to blow water inwardly from the interior trough cavity between the walls 5 and 7, while allowing for and assisting free release of water outwardly.

The base portion 2, as shown, is arched upwardly between its lateral bearing edge portions, adapting the strip C to be laid upon and secured to the flat surface of the sill B by the screws 3.

By upwardly arching the bottom as shown, a limited degree of adjustment of the free terminal edge portions of the strip is provided, by tightening or loosening the screws. In this manner the tongue 6 may be thrown upwardly or downwardly, adapting it to accurate fitting within the groove 15, and the wall 7 may also be proportionately adjusted. Said wall provides a strong, substantial abutting stop for the window so as to limit its movement definitely and properly for interfitting engagement with the sill strip.

The construction as a whole provides for complete sealing and protection by the weather strip, supplemented by the coping as made and applied. The tongue and groove members have sufficient resiliency to adjust themselves to each other, while the free edges of each strip member are completely concealed and protected within a generally rounded contour when in engagement.

The device is comparatively simple, cheap, and effective, and continuously durable. The proportions, dimensions, or specific details features may be changed or modified by the skilled mechanic, but all such changes are to be understood as within the scope of the following claims.

What I claim is:

1. In a casement window weather strip, the combination with a sill member having an attaching base provided with an inner sash engaging wall and an outer upwardly sloping wall having an inwardly turned flange, of a sash member having an upper securing flange and an outwardly disposed downwardly sloping wall reversed inwardly

and doubled upon itself providing an unattached resilient under-engaging flange for engagement with the flange of the sill member. 55

2. In a casement window weather strip, the combination with a sill member having an attaching base provided with an inner sash engaging wall and an outer upwardly sloping wall having an inwardly turned flange, of a sash member having an upper securing flange and an outwardly disposed downwardly sloping wall reversed inwardly and doubled upon itself providing an unattached resilient bottom embodying an outwardly open groove for engagement with the flange of the sill member. 65

3. In a casement window weather strip, the combination with a sill member having an upwardly arched bottom forming an attaching base provided with an inner sash engaging wall and an outer wall having an inwardly turned flange, of a sash member having a securing flange and an outwardly disposed wall reversed inwardly and doubled upon itself providing an inter-engaging flange for engagement with the flange of the sill member. 70

4. In a casement window weather strip, the combination with a sill member having an attaching base provided with an inner sash engaging wall and an outer wall provided at its bottom with partly punched out openings providing protected leak openings 85 and terminating in an inwardly turned flange, of a sash member having a securing flange and an outwardly disposed wall reversed inwardly and doubled upon itself providing an under-engaging flange for engagement with the flange of the sill member. 90

5. In sheet metal weather strips, the combination with an open top sill member having an inner vertical wall, an upwardly curved base and an outer upwardly extending inwardly flanged wall, of a sash member having an attaching flange, an outwardly projecting coping wall and a lower open sided double wall groove portion for engagement with the inwardly flanged wall of 100 the sill member. 95

In testimony whereof I hereunto affix my signature.

HARRY E. BRICKER.
